UNITED STATES PATENT OFFICE

155,823

DESIGN FOR A SIMULATED GEARSHIFT
DEVICE

Stuart Nelson Mann, Derby, N. Y.

Application December 26, 1947, Serial No. 143,351

Term of patent 7 years

(Cl. D34—15)

To all whom it may concern:

Be it known that I, Stuart Nelson Mann, a citizen of the United States, residing at Derby, in the county of Erie and State of New York, have invented a new, original, and ornamental Design for a Simulated Gearshift Device, of which the following is a specification, reference being had to the accompanying drawings, forming a part thereof.

In the drawings—

Fig. 1 is a perspective view of a simulated gearshift device, showing my design;

Fig. 2 is a side view thereof; and,

Fig. 3 is a sectional plan view thereof, taken on line III—III of Fig. 2.

I claim:

The ornamental design for a simulated gearshift device, as shown.

STUART NELSON MANN.
